UNITED STATES PATENT OFFICE.

FREDERICK J. GLEASON, OF WALPOLE, MASSACHUSETTS, ASSIGNOR TO STANDARD WOVEN FABRIC COMPANY, OF FRAMINGHAM, MASSACHUSETTS, A CORPORATION OF MASSACHUSETTS.

RUBBER ARTICLE.

1,188,348.

Specification of Letters Patent. Patented June 20, 1916.

Application filed November 20, 1915. Serial No. 62,619.

To all whom it may concern:

Be it known that I, FREDERICK J. GLEASON, a citizen of the United States, residing at Walpole, in the county of Norfolk and State of Massachusetts, have invented certain Improvements in Rubber Articles, of which the following description, in connection with the accompanying drawings, is a specification, like reference characters on the drawings indicating like parts in the several figures.

This invention relates to rubber articles having surfaces which are exposed to severe wear, such for instance as rubber heels and soles for shoes, and more specifically to that class of articles of this general character which contain plugs or inserts of some character designed to prevent slipping or to increase the wearing qualities of the article. It has been proposed heretofore to use metal in the inserts or plugs with which articles of this general character are provided, but such attempts have never proved successful from a commercial standpoint, so far as I am aware, due chiefly to the fact that no satisfactory way has been found of anchoring the metal parts in the article. It has usually been found that the metal parts become loose after the article has been in service only a relatively short time, and that they soon drop out so that the purpose for which they were employed is completely defeated.

It is the chief object of the present invention to overcome the difficulty just described, and to devise an article of the character indicated in which metal parts or inserts shall be anchored so securely that they will remain in place under ordinary conditions of service until practically worn out. The manner in which it is proposed to accomplish this object will be readily understood from the following description, reference being made to the accompanying drawings, in which—

Figure 1 is a perspective view of a rubber heel for a shoe having a friction plug secured therein and embodying the present invention; Fig. 2 is a perspective view showing the structure of the plug with which the heel shown in Fig. 1 is provided; Fig. 3 is a view similar to Fig. 2 showing a slightly modified construction; and Fig. 4 is a cross sectional view through a friction plug secured in a heel and embodying a further modification of this invention.

In the construction shown in the drawings and referring particularly to Figs. 1 and 2, 2 designates a rubber heel of the usual form having a friction plug 4 secured therein. This plug is constructed, as shown more clearly in Fig. 2, by folding together a sheet 6 of some soft metal and a sheet 8 of some non-metallic material such for instance as canvas, duck or other textile material. These two sheets of material are laid one on top of the other and are then folded or rolled together, as shown in Fig. 2, to form a roll 4' which preferably is somewhat oval in cross section. This roll is then cut into short plugs, each of the required length to be incorporated in a heel. This construction provides alternate layers of metal and canvas substantially throughout the plug. Preferably the canvas strip 8 is treated with a rubber cement or compound, as is usual in manufacturing plugs of this character, so that when the heel is vulcanized, the canvas will unite with or bond securely to the adjacent parts of the rubber body of the heel. I consider it preferable to extend the end of the sheet or strip 8 somewhat beyond the end of the metallic sheet 6 so that the outer peripheral surface of the plug will be composed entirely of the non-metallic material. In order to further unite the parts of the plug with each other, I prefer to use for the part 6 a sheet of lead coated or plated with copper since the copper reacts during the vulcanizing operation with the rubber composition in the canvas and makes a firm adhesive bond between the adjacent layers of the sheets 6 and 8. I regard this as an important feature of my invention. It is obvious that the copper and lead might be used in the form of an alloy; in fact a considerable variety of compositions could be used for this purpose although I prefer to use a soft metal in shoe heels and soles in order to avoid the presence of material that might abrade or scratch, to an objectionable degree, surfaces such for instance as hardwood floors, with which they might come in contact. I find it desirable to use lead because of its friction properties. The plug 4, as shown in Fig. 1, is inserted in the heel so that the sheets 6 and 8 lie transversely to the tread face and their edge portions thus are exposed to the wear on the tread face of the heel.

The form of plug shown in Fig. 3 differs

from that shown in Figs. 1 and 2 in that the metal sheet 6 is perforated, as indicated at 9. This construction is of advantage in that the metallic and non-metallic sheets in this case not only are so infolded with or inwrapped in each other that they are firmly secured together, but the material of the sheet 8 sinks into the apertures 9 and thus affords an additional means for interlocking the two sheets. This idea is carried somewhat farther in the construction shown in Fig. 4 in which the plug 10, corresponding to the plug 4 of Fig. 1, comprises several strips or layers 12 of soft metal, such as that above described, separated by layers of rubber. The metal pieces are perforated, as indicated at 15, and the rubber is squeezed into these perforations in the course of manufacture and thus mechanically locks the metal pieces in their proper positions. In this arrangement also I prefer to use metal parts of the character above described so that they will bond to the adjacent parts of the heel.

25 While the invention has been above described as embodied in a rubber shoe heel, it is obvious that it is equally applicable to other rubber articles, such for instance as shoe soles, crutch tips, rubber tires, etc., and 30 its application to such uses is regarded as falling within the scope of the present invention.

The article above described is in some respects an improvement on that disclosed in 35 my prior application Serial No. 23,490, filed April 23, 1915, but the claims of the present application are limited to subject-matter not disclosed in my earlier application, the broad claims being presented in the earlier 40 case.

Having thus described my invention, what I claim as new and desire to secure by Letters Patent of the United States is:

1. A rubber article, having a wearing surface and having a friction plug secured therein, said plug comprising layers of metal containing lead, and layers of non-metallic material mechanically interlocked with said layers of metal.
2. A rubber article having a wearing surface and having a friction plug therein comprising layers of friction metal in sheet form extending transversely to the said surface and layers of non-metallic material between the layers of said metal.
3. A rubber article having a wearing surface and having a friction plug therein comprising sheets of friction metal and textile material folded together and extending transversely to said surface, whereby the edges of the sheets are presented to the wear at said surface.

4. A rubber article having a wearing surface and having a friction plug therein comprising sheets of soft metal and non-metallic material inwrapped in each other and having their edges exposed to the wear at said surface.

5. A rubber article having a wearing surface and having a friction plug therein comprising sheets of friction metal and non-metallic material folded together and extending transversely to said surface, whereby the edges of the sheets are presented to the wear at said surface.

75 6. A rubber article having a wearing surface and having a friction plug secured therein, said plug comprising layers of metal containing copper, and layers of non-metallic material mechanically interlocked with said layers of metal.

7. A rubber article having a wearing surface and having a friction plug therein comprising layers of soft metal in sheet form extending transversely to the said surface, and layers of non-metallic material between the layers of said friction metal, said non-metallic material being united with the adjacent material of said article.

8. A rubber article having a wearing surface and having a soft metal in strip form arranged therein to present edge portions thereof to the wear on said surface.

9. A rubber article having a wearing surface and having lead in strip form arranged therein to present edge portions thereof to the wear on said surface.

10. A rubber article having a wearing surface and having a soft metal in strip form arranged therein to present edge portions thereof to the wear on said surface, and non-metallic material mechanically interlocked with said metal and bonded to the adjacent parts of said article.

11. A rubber article having a wearing surface and containing a soft metal arranged therein in layers extending transversely to said surface, said layers being perforated, and layers of other material bonded to the adjacent parts of said article and in firm engagement with said layers of metal.

12. A rubber article having a friction surface and having a soft metal, including lead and copper, in sheet form arranged in said article to present edge portions thereof to the wear on said surface, and non-metallic material mechanically interlocked with said metal and bonded to the adjacent parts of said article.

In testimony whereof I have signed my name to this specification.

FREDERICK J. GLEASON.
